Primary Examiner—M. N. Pandozzi

(57) **CLAIM**

The ornamental design for a motorcycle gas tank stylized teapot, as shown and described.

DESCRIPTION

FIG. 1 is an elevated perspective top view of the motorcycle gas tank stylized teapot, showing my new design;

FIG. 2 is a left side view of the motorcycle gas tank stylized teapot, the right side being a mirror image thereof;

FIG. 3 is a top plan view of the motorcycle gas tank stylized teapot;

FIG. 4 is a bottom plan view of the motorcycle gas tank stylized teapot;

FIG. 5 is a frontal view of the motorcycle gas tank stylized teapot; and,

FIG. 6 is a rear elevational view of the motorcycle gas tank stylized teapot.
